(57) **CLAIM**

The ornamental design for a license plate frame, as shown and described.

DESCRIPTION

FIG. 1 is a front view showing our new design for a license plate frame.

FIG. 2 is a right side view of the license plate frame of the present invention.

FIG. 3 is an enlarged view of the highlighted 3-3 portion of the license plate frame shown in FIG. 1;

FIG. 4 is a bottom view of the license plate frame of the present invention.

FIG. 5 is a back view of the license plate frame of the present invention.

FIG. 6 is a left side view of the license plate frame of the present invention.

FIG. 7 is a top view of the license plate frame of the present invention.

FIG. 8 is a perspective front view of the license plate frame of the present invention; and,

FIG. 9 is a perspective, exploded front view of the license plate frame of the present invention.
